[57] CLAIM

I claim the ornamental design for hunter's camouflage fabric, as shown and described.

DESCRIPTION

The file of this patent contains at least one drawing executed in color. Copies of this patent with color drawing will be provided by the Patent and Trademark Office upon request and payment of the necessary fee.

The sole FIGURE is a color photograph of a front view of a hunter's camouflage fabric showing my new design, the rear and edge views being plane and unornamented and, therefore, not shown.
